UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,197,032.

Specification of Letters Patent. Patented Sept. 5, 1916.

Application filed September 23, 1915. Serial No. 52,144.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler, No. 436532, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through a distributing mechanism to the magazine from which they started.

20 For the printing of tabular matter in which figures or the like are arranged in vertical columns with blank spaces or vertical rules between them, it is of course necessary that the successive slugs shall have 25 these spaces in like position so that they will aline or register when assembled side by side in the form, and for this reason, it is important for the operator to know the exact length of a composed group or line of 30 matrices.

35 It is the aim of my invention to facilitate this class of composition and to enable the operator to determine the length of the assembled groups or lines with the greatest 40 possible speed and facility. The manner in which this result is accomplished will be fully explained in the detailed description to follow and finally pointed out in the 45 claims.

50 In the accompanying drawings, I have shown my invention merely in preferred form and by way of example and as applied to a linotype machine, but obviously many changes and variations may be made therein and in its mode of application, which will still be comprised within its 55 spirit. Generally speaking, I desire it to be understood that I do not limit myself to

any specific form or embodiment, except in so far as such limitations are specified in 55 the claims.

Referring to the drawings: Figure 1 is a detached perspective view of the composing mechanism of a linotype machine having my invention applied thereto; Fig. 2 is a section 60 on the line 2-2 of Fig. 3; Fig. 3 is a horizontal section through the parts shown in Fig. 1, showing the use of my improvements in connection with an assembled group or line of matrices; and Fig. 4 is a 65 section on the line 4-4 of Fig. 3.

The matrices X, as they are released from the magazine (not shown), drop in front of the star wheel A¹, which advances them progressively into the channeled assembler 70 A against the yielding resistant or finger C carried by the slide C¹. When the composition of the line is completed, the assembler is shifted into registration with the intermediate channel B, through which the line 75 is carried to the casting mechanism, all in the usual way. An assembled group or line of matrices X is shown in Fig. 3, and in order to determine the exact length thereof, the following mechanism is employed in accordance with my invention: Attached to the front wall of the assembler A is a bracket A² giving support to a transverse slide D having a straight reduced portion 80 D¹ arranged to be projected into the assembler channel behind the last matrix of the composed group or line, so as to serve as a fixed abutment or gage against which the line may be compressed and measured. A 85 spring D² arranged between the bracket A² and a thumb piece D³ on the front end of the slide D holds the latter normally with its reduced portion D¹ out of the assembler channel, and consequently out of the path of the incoming matrices. The compression of 90 the assembled group or line against the gage D¹ is effected by a forked member E arranged so as to move in and lengthwise of the assembler channel and adapted to engage the leading matrix therein directly 100 through notches or openings C² formed in the opposite edges of the resistant C. The member E is carried by an arm E¹ extended laterally from a sleeve E³ slidably arranged upon a rod E⁴ supported in a bracket B¹ secured to the front wall of the intermediate

105

channel B. The sleeve E³ is shifted longitudinally along the rod E⁴ by a handle E² integral with the arm E¹, and the sleeve is splined to the rod, so as to be capable of 5 only a sliding movement thereon, by a longitudinal strip E⁵. This strip E⁵ is provided on its upper face with rack teeth meshing with a gear E⁶ fast upon a transverse shaft or stud E⁷ supported in the bracket B¹ and 10 provided at its front end with a rotary dial plate E⁸ co-operating with a fixed mark or pointer E⁹ on the upper end of the bracket. A spiral spring E¹⁰ secured at one end to the bracket B¹ and its opposite end to the 15 shaft E⁷ serves constantly to rotate the gear E⁶ clockwise so as to hold the dial plate E⁸ in its zero position and the member E and the connected parts normally in the position shown in Fig. 1 and out of the path of 20 movement of the assembler A.

The operation of the parts is as follows: When a group or line of matrices has been 25 assembled and it is desired to determine the exact length thereof, the operator grasps the handle E² and moves the member E¹ toward the matrix line, and either before or after the member is brought into engagement with the leading matrix, he pushes rearwardly, by means of his thumb, the 30 slide D whose reduced portion D¹ is thus projected behind the last assembled matrix and serves as a fixed abutment against which the line is compressed by the member E. This movement of the member E rotates the 35 dial plate E⁸, which in conjunction with the mark or pointer E⁹ indicates to the operator the exact length of the line composed. The operator then releases his hold upon the parts and they are immediately restored to 40 normal or inactive position by the springs E¹⁰ and D² respectively, allowing the immediate forwarding of the composed line if completed and permitting the composition of a further group or line to be proceeded 45 with. In this way, the operator is enabled to determine instantly and at pleasure the exact length of the group or line composed, so that in setting tabular matter he may be advised as to the number of spaces required 50 to fill out a line or the particular point at which they are to be inserted.

It will be noted that the present arrangement in the preferred form described is such that the assembled group or line is measured 55 between elements which are independent of any of the machine parts. This is advantageous in that it insures greater accuracy in the measurement, the wear to which the machine parts are constantly subjected being 60 entirely eliminated. Heretofore the measurement has been taken through or against the star wheel A¹ or the line resistant C or both, with the result that it has not always been exact or true, the star wheel particularly being subject to rapid wear.

As previously stated, I have shown my invention merely in preferred form and by way of example, but obviously many modifications and alterations therein will readily suggest themselves to those skilled in the art without departure from its scope.

Having thus described my invention, its construction and mode of operation, what I claim and desire to secure by Letters Patent of the United States is as follows:

1. In a typographical machine, the combination of means for assembling matrices in a line or group, a member movable to a fixed and definite position behind the last assembled matrix to serve as an abutment, against which the line may be compressed, and a movable measuring device for so compressing the line.

2. In a typographical machine, the combination of an assembler wherein the matrices are composed in a line or group, a movable member mounted on the assembler so as to be projected to a fixed and definite position behind the last assembled matrix, and a movable measuring device for compressing the line against said member as an abutment, for the purpose described.

3. In a typographical machine, the combination of a movable assembler wherein the matrices are composed in a line or group, a movable member carried by the assembler and arranged thereon so as to be projected to a fixed and definite position behind the last assembled matrix, and a movable measuring device mounted independently of the assembler for compressing the line or group endwise against the said member as an abutment.

4. In a typographical machine, the combination of means for assembling matrices in a line or group, with a member movable at will behind the last assembled matrix to serve as an abutment against which the line may be compressed, and a measuring device operable manually for so compressing the line, together with automatic means for restoring said parts to their normal position after each operation.

5. In a typographical machine, the combination of a movable assembler wherein the matrices are composed in a line or group, with a movable member carried by the assembler and arranged thereon in position to be projected behind the last assembled matrix, and a measuring device mounted independently of the assembler and movable to compress the line or group endwise against said member as an abutment, together with means for automatically withdrawing the measuring device after its operation from the path of movement of the assembler.

6. In a typographical machine, the combination of means for assembling the matrices in a line or group, manually controlled mechanism, independent of the assembling

means, for determining the length of the assembled line or group, and an indicator associated with said mechanism.

7. In a typographical machine, the combination of means for assembling the matrices in a line or group, mechanism, normally inactive but operable at will, to determine the full length of the composed line or group, and an indicator associated with 10 said mechanism.

8. In a typographical machine, the combination with means for assembling matrices in a line or group, of mechanism distinct from the assembling means for determining the length of the assembled line or group, said mechanism including a member movable behind the last assembled matrix to serve as an abutment against which the line is compressed, and movable means 20 to coöperate with the assembled line and to indicate the length thereof when compressed.

9: In a typographical machine, the combination with means for assembling matrices in a line or group, of mechanism distinct from the assembling means for determining the length of the assembled line or group, said mechanism including a member movable behind the last assembled matrix to serve as a fixed abutment, a second member for compressing the line endwise against the abutment, and an indicator controlled by the second member to show the exact length of the line when compressed.

35 10. In a typographical machine, the combination of a movable assembler wherein the matrices are composed in a line or group, and mechanism distinct from the assembling means for determining the length of the assembled line or group, the said mechanism including a movable member carried by the assembler and arranged thereon in position to be projected behind the last assembled matrix, a second member supported independently of the assembler and movably arranged so as to compress the line against the other member, and an indicator controlled by the second member.

45 11. In a typographical machine, the com-

bination of means for assembling matrices 50 in a line or group, and mechanism distinct from the assembling means for determining the length of the assembled line or group, the said mechanism including two members between which the line is compressed and 55 which engage directly with the matrices at the opposite ends of the line.

12. In a typographical machine, the combination with means for assembling matrices in a line or group, of mechanism distinct from the assembling means for determining the length of the assembled line or group, said mechanism including a member movable behind the last assembled matrix to serve as a fixed abutment, a second 60 member for compressing the line endwise against the abutment, the two said members being arranged to engage directly the matrices at the opposite ends of the line, and an indicator controlled by the second member 70 to show the length of the compressed line.

13. In a typographical machine, the combination of the assembler A wherein the matrices are assembled in a line or group, and provided with the transversely movable 75 slide D arranged thereon in position to be projected behind the last assembled matrix, the longitudinally movable member E operable manually to compress the line endwise against the slide D, and the rotary dial 80 E^s operated by the longitudinal movement of the member E.

14. In a typographical machine, the combination of the assembler A wherein the matrices are assembled in a line or group 85 and provided at its receiving end with the transverse spring-pressed slide D, the longitudinally movable member E operable manually mounted independently of the assembler for compressing the assembled line 90 against the slide D when the latter is in its projected position, and the spring-actuated dial E^s operated by the longitudinal movement of the member E to indicate the length 95 of the compressed line.

In testimony whereof, I have affixed my signature.

DAVID S. KENNEDY.
